(57) **CLAIM**

The ornamental design for a spreader, as shown and described.

DESCRIPTION

FIG. 1 is a front perspective view of a spreader showing our new design;

FIG. 2 is a front elevation view thereof;

FIG. 3 is a rear elevation view thereof;

FIG. 4 is a right side elevation view thereof;

FIG. 5 is a left side elevation view thereof;

FIG. 6 is a top plan view thereof;

FIG. 7 is a bottom plan view thereof; and,

FIG. 8 is a rear perspective view thereof.

The line shading in FIGS. 1-8 represents contour and not surface ornamentation. The broken lines illustrate the portions of the spreader that form no part of the claimed design.
